United States Patent Office.

J. S. REID, OF ORANGE, INDIANA.

Letters Patent No. 96,961, dated November 16, 1869.

STAND FOR EXHIBITING PHOTOGRAPHS, &c.

The Schedule referred to in these Letters Patent and making part of the same.

To all whom it may concern:

Be it known that I, J. S. REID, of Orange, in the county of Fayette, and in the State of Indiana, have invented a certain new and useful Improvement in Photographic Stand or Album; and do hereby declare that the following is a full, clear, and exact description thereof, reference being had to the accompanying drawings, and to the letters of reference marked thereon.

The nature of my invention consists in the construction and general arrangement of a photographic-stand, which is revolving, and constitutes a neat ornament for the parlor-table.

In order to enable others skilled in the art to which my invention appertains, to make and use the same, I will now proceed to describe its construction and operation, referring to the annexed drawings, which form a part of this specification, and in which—

Figure 1 is a side elevation, and

Figure 2, the same, in section.

A represents a stand or bed-piece, in the centre of which is an upright stationary rod, B, of suitable height.

On the rod B is placed an octagon cylinder, or base, C, each side of the same being large enough to hold a photograph of the usual size.

The cylinder C has a bottom, D, but is open at the top.

Through the centre of the bottom D is a hole, over which is placed a hollow rod, E, of such height, that when placed on the rod B it will rest on the same, the upper part of the rod E being solid, as shown in fig. 2.

On top of the octagon base C is placed another cylinder, F, which is narrower at the top than at the base, having at its lower end a flange extending all around the same.

The cylinder F is octagon shaped at the bottom, to correspond with the shape of the base C, but, narrowing toward the top, forms there a square, leaving places for four-square and for round or oblong photographs, as seen in fig. 1.

Pins *a a*, passing through the flange at the bottom of the cylinder F, enter into holes on the upper rim, on the base C, and hold the former in its proper position.

On top of the cylinder F, a cap, G, is placed, which, at its bottom, is square, to correspond with the four sides of the top of the cylinder, and, narrowing at the

top, forms a cone with four sides, on each of which is a space for a vignette.

The cap is held in its position by pins *b b*, as shown in fig. 2.

On top of the cap G is placed a knob, H, which gives a beautiful finish to the whole stand.

It will be seen, that thus constructed, I have a revolving album, which contains both square and oblong photographs, and, as it can be finished off in any style desired, presents a neat and beautiful ornament.

If the base C is made of more than eight sides, the parts above will be made to correspond with the increased number of sides, and, of course, will contain so many more pictures.

Inside of the base C and cylinder F, I may place a cylinder, I, of smaller size, but made so as to correspond in shape with the two former, and in which another set of pictures may be placed.

In that case, one of the sides of the base C, as well as one in the cylinder F, is left without a picture, the glass only remaining, (all the sides of the outside stand are provided with glass covering the pictures,) so that the pictures in the inner cylinder may be seen through the same.

The top of the inner cylinder rests and revolves on the top of the rod E, and the knob H is provided with a rod, L, passing through the centre of the cap G, and, being threaded on its lower end, into a nut in the top of the cylinder I, so that by turning the knob H the inner cylinder can be revolved, and show all the pictures in succession, through the open sides mentioned, of the outside stand.

The whole stand may be made of any material desired, and ornamented in any way to suit the taste.

Having thus fully described my invention,

What I claim as new, and desire to secure by Letters Patent, is—

The knob H, rod L, and cylinder I, in combination with the cap G, cylinder F, base C, rod E, and bed-piece A, all constructed as described, so as to form a double revolving photographic-stand, or album, containing pictures of different size, substantially as herein set forth.

In testimony that I claim the foregoing, I have hereunto set my hand, this 6th day of August, 1868.
